UNITED STATES PATENT OFFICE.

CHARLES G. FOOTE, OF DENVER, COLORADO.

ROCK-DRILL.

SPECIFICATION forming part of Letters Patent No. 783,032, dated February 21, 1905.

Application filed December 14, 1903. Serial No. 185,140.

To all whom it may concern:

Be it known that I, CHARLES G. FOOTE, a citizen of the United States of America, residing in the city and county of Denver and State of Colorado, have invented certain new and useful Improvements in Rock-Drills; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to improvements in rock-drills; and it consists of the features, arrangements, and combinations hereinafter described and claimed, all of which will be fully understood by reference to the accompanying drawings, in which is illustrated an embodiment thereof.

In the drawings, Figure 1 is a top or plan view of the machine. Fig. 2 is a section taken on the line 2 2, Fig. 5. Fig. 3 is a sectional view in detail and on a larger scale, taken longitudinally through the chuck extremity of the drill-holder. Fig. 4 is an end view of the same looking in the direction of the arrow in Fig. 3. Fig. 5 is a vertical longitudinal section of the complete machine. Figs. 6 and 7 are detail views illustrating the construction and operation of the device for imparting the rotary movement to the drill-holder. Fig. 8 is a sectional view in detail and on a larger scale, illustrating the construction whereby the drill-holder is drawn rearwardly against the power-spring by the spiral cam of the rotary cylinder and released to allow the spring to move the drill-holder forwardly. Fig. 9 is a section taken on the line 9 9, Fig. 8. Fig. 10 is a detail view illustrating the manner of mounting the machine. Fig. 11 is a section taken on the line 11 11, Fig. 10.

The same reference characters indicate the same parts in all the views.

Let the numeral 5 designate the guide-shell, provided with a foot 6, beveled or flared to engage a counterpart socket formed in a holder 7, provided with a hinged clamp 8. This part 8 is hinged to the body of the holder at 9 and

secured at its opposite extremity by a stud-bolt 10. This holder is clamped to the column or supporting bar or shaft (not shown) when the drill is in actual use. The foot is locked in place on the holder by an adjustable part 12, held in place by a stud-bolt 13, passing through a slot 14 in the part 12. The part 12 is adjustable for the purpose of tightening or loosening the holder on the foot by means of a wedge-shaped key 15, passing between the part 12 and a relatively stationary shoulder formed on the holder. The key 15 is provided with ratchet-teeth 17, engaged by a spring-actuated dog 18, whereby the key is locked in the adjusted position.

A feed-screw 19 of ordinary construction is journaled in the guide-shell and threaded in a nut 20, made fast to the casing 21, which is slidably connected with the guide-shell by tongues 22, formed on the casing and engaging counterpart grooves formed in the shell. The feed-screw is operated by a hand-crank 23.

Mounted to rotate in the casing is a cylinder 24, composed of an outer part *a* and two inner parts *b* and *c*. The outer part is provided with interiorly-projecting lugs *d*, which engage the outer surface of the parts *b* and *c*. The space between the inner surface of the part *a* and the outer surface of the parts *b* and *c* is preferably filled with Babbitt metal *g*. The part *a* is composed of two twin sections *a'* and *a''*, having ears *a'*, provided with registering openings through which are passed bolts *a'*, secured by nuts, whereby the part *a* is securely clamped to the parts *b* and *c*. In order to absolutely insure the movement of all of the parts of the cylinder 24 in unison, stud-bolts *a'* are employed to lock the parts together. Upon the rear extremity of the part *c* of the cylinder is formed a spiral cam 26, which is engaged by a projection 27, made fast on the drill-holder 28. The parts *b* and *c* are hollow to receive the drill-holder, and within the part *b* is located a power-spring 30, which surrounds the drill 31. This drill passes axially through the entire machine and may be removed at its rear extremity while the machine is in position adjacent to and pointing toward the breast of the rock. One extremity of the power-spring engages the rear end of the part *b* in-

65

teriorly, while its forward extremity engages a shoulder 32, with which the drill-holder is provided.

The drill-holder and drill are reciprocated by the rotation of the cylinder containing the cam-groove. This rotary action of the cylinder may be imparted in any suitable manner. As shown in the drawings, an electric motor 33 is used for supplying the power. This motor is so located that its axis coincides with the axis of the drill 31, which passes therethrough. It is evident that the motor may be connected with the rotary cylinder in any other suitable manner. The armature of the motor is suitably connected to rotate a collar 34, which is interlocked with the cylinder by conical projections 35, engaging counterpart recesses formed in the rear end of the part *b* of the cylinder. The collar 34 has a limited longitudinal movement on the armature of the motor and is held in operative relation with the cylinder by a coil-spring 36, which surrounds a rearward extension of the collar and is located between a shoulder of the collar and a stop 37, applied to the motor-armature. In case of accident or if for any reason the rotation of the cylinder is suddenly stopped or resisted with sufficient force to result in breakage of some of the parts of the machine if its movement is continued the spring 36 will yield, allowing the collar 34 to move rearwardly sufficiently to disengage itself from the cylinder, thus allowing the motor to continue its operation, while the operating parts of the drill remain stationary.

The shape of the cam 26 formed on the cylinder is clearly illustrated in Fig. 8. When the drill-holder is at its forward limit of movement, the projection 27 thereof engages the point A of the cam, which will be termed the "initial point." Then as the cylinder is rotated the cam is turned, and the projection 27 of the drill-holder being in engagement therewith causes the latter to be moved rearwardly against the spring 29 until the terminal point B of the cam is reached. Here the projection 27 of the drill-holder is released and travels forward in a straight line with the drill-holder from the point B to the point A, the forward movement of the drill-holder being imparted by the recoil of the spring 29, which has been placed under tension by the rearward movement of the drill-holder.

To the forward extremity of the drill-holder is secured a toothed wheel 38 by a set-screw 39, passing through an opening in the forward extension of the collar of the wheel and threaded in the drill-holder. At this point the body of the drill-holder 28 is connected with a reduced forward part 40 by the set-screw or stud-bolt 39. So far as the operation of the drill-holder is concerned the parts 28 and 40 are virtually integral and operate in unison. Hence when the term "drill-holder" is hereinafter referred to without

using a reference character it must be understood that the entire drill-holding device is intended.

Between the collar of the toothed wheel and the bearing 41 of the casing is located a buffer-spring 42. The toothed wheel 38 is prevented from rotating with the cylinder by a pawl 43, hinged at 44 to a stationary part 45, secured to the casing by a screw 46. This pawl is engaged by a leaf-spring 47, also held in position by the screw 46.

Below the pawl 43 the wheel 38 is engaged by a tooth 48 of a plate 49, pivotally connected with the casing at its rear extremity, as shown as 49^a, and normally held at its limit of downward movement by a spring 49^c. This tooth 48 is provided with a projection C, extending upwardly from the body of the tooth. As the drill-holder is moved rearwardly against the power-spring the tooth 48 first passes between two teeth or cogs of the wheel 38. Then as the rearward movement of the drill-holder is continued the wheel engages the upward projection C, which forms a stop and causes the plate 49 to turn upwardly on its pivot 49^a, and this upward movement (the tooth 48 engaging the side of the wheel, see Fig. 2) turns the wheel and drill-holder one tooth in a direction opposite the rotation of the cylinder. Then as the drill-holder moves forwardly the wheel becomes disengaged from the tooth 48, while the plate 49 returns to its normal position and is ready to perform the same function every time the drill-holder moves rearwardly.

The forward extremity of the drill-holder is provided with lateral openings in which are placed locking-pieces 50, whose inner edges are adapted to engage the drill 31, while their outer edges project from the openings in the drill-holder to engagement with a surrounding collar 51. The outer edges of the pieces 50 are inclined, being widest at their forward extremities. The inner surface of the collar 51 is shaped to force the pieces 50 inwardly against the drill-holder, whereby they are caused to lock or clamp the latter securely in place as the collar 51 is moved forwardly. In the rear of the collar 51 is a washer 52, and in the rear of this washer is a screw-sleeve 53, which is threaded on the drill-holder and is adapted to be screwed against the washer by the use of a spanner-wrench engaging pins 54, mounted on the said screw-sleeve. It is evident that by turning the sleeve in the one direction or the other the drill may be tightened in the drill-holder or made loose therein, as desired. If it is desired to remove the drill from the drill-holder, it is only necessary to turn the sleeve 53 in a direction to cause it to move rearwardly a sufficient distance to allow the collar 51 to be moved in the same direction a sufficient distance to allow the drill 31 to be drawn rearwardly through the drill-holder. This is a very con-

venient way of removing dulled drills and substituting sharp ones, and by reason of my improved construction much time is gained in this part of the work. It is well known 5 that drills while in use become quickly dull and must frequently be removed for the purpose of resharpening, and of course every time a dull drill is removed a sharp one must be substituted in its place. By reason of the 10 drill being removable from the rear end of the machine it is not necessary to turn the casing on its support in order to make room to remove the drill from the front, as is usually required in taking out one drill and substituting another. Any length of drill-bit 15 may be employed.

From the foregoing description the use and operation of my improved rock-drill will be readily understood. The wires or electric conductors 20 56, connected with the motor, may lead to any suitable source of electricity. When it is desired to operate the drill, the current is turned into the motor, and the rotation of the latter's armature imparts a corresponding movement to the cylinder 24. 25 From what has been heretofore explained it will be understood that this cylinder includes a number of parts which are connected together and rotate in unison. Every time the 30 cylinder completes a revolution the drill-holder is moved rearwardly against the spring 30 and released, whereby the drill-holder is thrown forwardly by the recoil of the spring. This forward movement may be given any 35 desired force, depending on the strength of the power-spring employed. It is evident that the number of strokes of the drill will depend on the speed of the motor, and this may be regulated as desired. Every time the drill- 40 holder moves rearwardly through the instrumentality of the cam 26, as heretofore explained, the toothed wheel 38 is made to engage the tooth 48 of the plate 49, whereby the wheel, together with the drill-holder and 45 drill, is given a rotary movement of a degree equal to what may be termed "one tooth" of the wheel, or the distance from the center of one tooth to the center of the other tooth, practically. In this way the necessary rotary 50 movement is imparted to the drill and drill-holder during the operation. As the cylinder 24 is rotated the pawl 43, engaging the toothed wheel 38, prevents the wheel from rotating in the same direction with the 55 cylinder 7, and when the toothed wheel and drill-holder are rotated it is in a direction opposite the rotary movement of the cylinder, as will be clearly understood from the drawings and description.

60 It will be observed by an inspection of the drawings that there is a space h between the forward extremity of the cylinder part b and the rear or cam extremity of the cylinder part c . The space h (see Fig. 8) is of sufficient 65 width to allow the projection 27 of the drill-

holder to pass. Hence if the drill is forced against the rock with sufficient pressure to drive the drill-holder against the power-spring 29 and compress the latter sufficiently to cause the pin 27 to occupy a position forward of the 70 cam or in the space h between the two cylinder parts it is evident that the motor and the entire cylinder 24 may rotate freely without any movement whatever of the drill-holder and drill-bit, since under the conditions stated the 75 entire cam will be located forward of the projection 27. This is an important feature, since it will prevent breakage of the mechanism under certain circumstances. Again, if the drill is pressed against the rock with sufficient force to move the drill-holder longitudinally in the cylinder a portion of the distance between the parts A and B of the cam it is evident that the length of the drill's stroke 80 will be correspondingly diminished. 85

Having thus described my invention, what I claim is—

1. In a rock-drill, the combination with a guide-shell and a casing slidable thereon, of a hollow cylinder mounted to rotate in the casing, a power-spring located in the cylinder, the latter being provided with a cam, and a hollow drill-holder entering the cylinder and having a projection engaging the cam of the rotary cylinder, whereby as the latter is rotated, the drill-holder is moved rearwardly against the power-spring and released. 90

2. The combination with a casing, of a cylinder mounted to rotate therein, the cylinder being hollow, a power-spring located in the cylinder the latter being provided with a cam, a hollow drill-holder entering the hollow of the cylinder and having its axis in line with the axis of the cylinder, the drill-holder being engaged by the cam of the cylinder as the latter is rotated, whereby the drill-holder is forced rearwardly against the power-spring and released, the recoil of the spring acting to throw the drill-holder forwardly causing the drill to strike the rock with the necessary force. 100 105

3. In a drill, the combination with a suitable support, of a hollow rotary part, a hollow drill-holder adapted to enter said part and having its axis in line with the rotary part, the rotary part being provided with a cam, and the drill-holder being provided with a projection engaging the cam, whereby as the cylinder is rotated, the drill-holder is forced rearwardly and released, and a power-spring acted on by the drill-holder during its rearward movement to place the spring under tension, the recoil of the spring acting to drive the drill-holder forwardly when the latter is released by the cam. 110 115

4. The combination with a suitable support, of a hollow rotary part provided with a cam, a hollow drill-holder entering said part and acted on by the rearwardly, a power-spring 120 125 of the drill-holder.

BEST AVAILABLE COP

783,032

its rearward movement, and a drill suitably connected with the drill-holder and passing entirely through the machine whereby it is removable at the rear.

5 5. In a rock-drill, the combination with a suitable support, of a hollow drill-holder, and a drill passing through the drill-holder and projecting from the rear of the machine, the drill being suitably connected with the drill-holder, and suitable means for imparting a reciprocating movement to the drill-holder, comprising a hollow rotary part which the drill enters, a spring in the rotary part, the latter being provided with a cam adapted to engage 10 the drill-holder and force the latter rearwardly against the spring in the hollow rotary part.

6. In a rock-drill, the combination of a drill and mechanism for reciprocating the same, the drill being of sufficient length to extend 20 entirely through the machine from front to rear, the reciprocating mechanism of the drill being formed hollow to permit the removal and insertion of drills at the rear of the machine, the drill being formed of sufficient 25 length for the purpose, the hollow drill-holder through which the drill passes, a hollow rotary part surrounding the drill-holder and provided with a cam engaging the drill-holder, and a spring located in the rotary part, the 30 cam of the latter acting to force the drill-holder against the spring and release it as described.

7. In a rock-drill, the combination with a suitable casing, of a hollow drill-holder, a hollow rotary cylinder having its axis in line with the axis of the drill-holder, the drill-holder being adapted to enter the cylinder, a drill passing through the drill-holder and cylinder and adapted to be removed from the rear of 40 the machine, a power-spring located in the hollow of the cylinder and having its forward extremity engaging a stop with which the drill-holder is provided, the cylinder being provided with a cam acting on a projection of 45 the drill-holder, whereby as the cylinder is rotated the drill-holder is forced rearwardly against the spring and released, the latter acting to drive the drill-holder and drill forwardly.

50 8. In a rock-drill, the combination of a hollow drill-holder, a hollow rotary cylinder having its axis in line with that of the drill-holder, the drill-holder entering the cylinder, a connection between the cylinder and drill-holder 55 whereby the rotary action of the cylinder imparts movement to the drill-holder in one direction, a spring for moving the drill-holder in the opposite direction, a motor for operating the rotary cylinder, and a suitable operating connection between the motor and the cylinder.

9. The combination of a hollow drill-holder, 60 in which the drill-holder is held in position between the cylinder and the drill-holder, whereby as the cylinder

inder is rotated the drill-holder is moved in one direction, a power-spring connected in operative relation with the drill-holder for imparting the forward movement thereto, a motor whose armature is in line with the axis of the drill-holder and cylinder; a collar interposed between the motor and the rotary cylinder, the collar being provided with pins adapted to enter recesses formed in the rear extremity of the cylinder, and a coil-spring 75 located in the rear of the collar, whereby the latter is yieldingly retained making it possible for the collar to continue its rotation independently of the rotary cylinder.

10. In a drill, the combination with a suitable casing, of a drill-holder, a toothed wheel made fast to the drill-holder, a plate pivotally connected to the casing and having a tooth adapted to pass between two teeth of the toothed wheel as the drill-holder is moved 80 rearwardly, the tooth of the pivoted plate having an upward projection whereby as the rearward movement of the drill-holder is continued, the plate is raised sufficiently to impart a partial rotary movement to the wheel 85 and drill-holder, and suitable means engaging the toothed wheel to prevent the latter from moving in a direction the reverse of that imparted by the pivoted plate.

11. In a rock-drill, the combination with a suitable casing, of a hollow cylinder mounted to rotate therein, a power-spring located in the rear portion of the cylinder, a hollow drill-holder entering the cylinder and engaging one extremity of the power-spring, a cam 95 formed on the inner part of the cylinder adjacent the drill-holder and adapted to engage a projection on the drill-holder to impart a reciprocating movement to the latter, and the cylinder being further provided with a space 100 forward of the cam, of sufficient width to permit the rotation of the cylinder while the drill-holder remains stationary, when the drill-holder is forced against the power-spring sufficiently to cause the projection of the drill-holder to occupy the said space forward of the cam.

12. The combination with a suitable casing, of a hollow cylinder mounted to rotate therein and composed of two parts transversely 115 separated and an outer coöperating part surrounding the two separated parts, one of the inner parts having a cam provided with a spiral face for the lift and a perpendicular face for the drop, and a drill-holder entering the said cylinder and having a radial projection entering the space between the inner parts of the cylinder and acted on by the cam, and a power-spring located in the cylinder and engaged by the drill-holder, whereby the radial projection of the drill-holder is normally held 120 against the cam-face.

13. The combination with a suitable casing, of a hollow cylinder mounted to rotate therein and composed of two parts transversely sep- 125

BEST AVAILABLE COP^Y

5

arated and an outer coöperating part surrounding the two separated parts, one of the inner parts having a cam provided with a spiral face for the lift and a perpendicular face for the drop, and a drill-holder entering the said cylinder and having a radial projection entering the space between the inner parts of the cylinder and acted on by the cam, a transverse space being left between the separated parts of the cylinder forward of the cam to allow

the radial projection of the drill-holder to enter when the drill is forced against the rock to compress the power-spring sufficiently for the purpose.

In testimony whereof I affix my signature in presence of two witnesses.

CHARLES G. FOOTE.
